UNITED STATES PATENT OFFICE

2,313,687

CEILING STRUCTURE

Stephen P. Walker, Winnetka, and Albert A. Schramm, Chicago, Ill., assignors to United States Gypsum Company, Chicago, Ill., a corporation of Illinois

Application May 6, 1940, Serial No. 333,462

18 Claims. (Cl. 189—65)

This invention relates to ceilings and more particularly to sound absorbent illuminated ceilings of the suspended type. Ceilings of this type usually comprise a suitable framework suspended from a permanent ceiling or other suitable sub-structure and supporting preformed perforated or foraminous tile and sound absorbent material on suitable furring strips or runners. Various types of preformed acoustical tile may, of course, be used. However, the tile in the embodiment disclosed herein are preferably perforated sheet metal panels having upturned edges forming beaded flanges adapted for removable engagement with the supporting runners.

The panels or so-called tile may support suitable sound absorbent material which may be spaced therefrom by means of a grid or the like supported in the panel, and the entire structure, when assembled, provides an effective sound absorbent ceiling.

It is an object of the present invention to provide an illuminated sound absorbent ceiling structure in which the illumination is preferably of a fluorescent type and wherein the ceiling comprises paneled spaces or strips with comparatively narrow coffer spaces therebetween. Elongated trough-like reflectors having tubular fluorescent lighting units associated therewith are supported in the coffer spaces with the open sides of the reflectors substantially flush with the surface of the panels.

Another object is the provision of a suitable framework particularly adapted to removably support the panels and reflector units and control units associated therewith, and in which the entire structure may quickly and easily be manufactured and installed at a minimum expense.

A further object is the provision of an effective sound absorbent mounting for the wiring channels or so-called control housings in which are enclosed and supported all of the control elements, including the wiring, sockets, and other apparatus for supporting and energizing the usual fluorescent tubes or lamps. Any suitable control elements may be used in the control housings, as the control elements per se form no part of the present invention and the control assemblies, including the housings or channels and elements therein, may be referred to herein as control units. The mounting for the control units is particularly effective in eliminating the usual sixty-cycle hum which is often an objectionable feature of this type of lighting equipment.

Another object is the provision of a new and novel means for supporting baffle plates in the

reflector whereby they may easily be inserted or removed and at the same time are hinged in such a manner that they may easily be unlatched and suspended from one side of the reflector to enable the convenient insertion and removal of the fluorescent tubes or to permit other servicing of the device.

It is also an object to provide suitable panel and reflector supporting brackets and a novel relationship thereof in the complete assembly, whereby the entire ceiling may very quickly and easily be assembled, and whereby the comparatively rigid and strong reflector is so supported and related to the rest of the structure as to assist in retaining the ceiling surface in horizontal alignment.

The invention also contemplates the provision of an illuminated sound absorbent ceiling structure in which the light is more evenly distributed and sharp line cut-offs and consequent contrasts are prevented, particularly adjacent the junction of the reflectors and tile. Various elements are also adjustable to enable accurate alignment of the tile and reflectors in the same plane.

Further objects will be apparent from the specification and the appended claims.

In the drawings:

Fig. 1 is a bottom view of a portion of a ceiling and illustrates one embodiment of the invention.

Fig. 2 is a top view of the embodiment illustrated in Fig. 1.

Fig. 3 is a transverse sectional view through the embodiment shown in Figs. 1 and 2, and is taken on a line substantially corresponding to lines 3—3 thereof.

Fig. 4 is a fragmentary sectional view taken on a line substantially corresponding to lines 4—4 of Figs. 2 and 3, and illustrates the overlapping joint of the reflector sections and also the general assembly and relationship of the supporting elements.

Fig. 5 is a top view of the joint of the overlapping reflector sections.

Fig. 6 is a detailed sectional view through the overlapping joint of the reflector sections and is taken on a line substantially corresponding to lines 6—6 of Figs. 4 and 5.

Fig. 7 is a transverse sectional view through the reflector and wiring channel or control unit and illustrates the method of mounting the baffle plates.

Fig. 8 is a detailed perspective view of the slotted portion of the reflector and the hinge end of the baffle plate which is adapted to be inserted in the slot.

Fig. 9 is a perspective view partially in section of the furring strip for supporting the panels and the reflectors and further illustrates the clip arrangement for supporting the furring strip and reflectors.

Fig. 10 is a fragmentary detail view partially in section of clips adapted to support the furring strip shown in Fig. 9.

Referring to the drawings in detail, the embodiment illustrated comprises a plurality of transverse furring members or bars 1 of a conventional type, preferably channel irons or the like, and these members may be supported from a permanent ceiling or other substructure by means of suitable wires or cables 2, any number of which may be used in order properly to support the furring members 1. The furring members are provided with dependent L-shaped hangers 3 which may be secured to the furring members in any suitable manner, preferably by being wired thereto as shown at 4. The hangers 3 are also preferably channel irons of a suitable size so that their flanges fit over the furring members 1, as shown in Fig. 3, and properly retain the hangers in alignment.

The hangers 3 are spaced throughout the ceiling structure to provide alternate panel spaces and coffer spaces between rows of hangers, as shown particularly in Figs. 1, 2, and 3, and the downwardly extending arms of the hangers are arranged to support suitable sheet metal runners 5 in the manner shown in detail in Fig. 10.

As disclosed in Fig. 9, the runners 5 each comprise a horizontal body portion 6 having inturned edges with downwardly extending converging flanges 7. The flanges 7 are provided adjacent their lower edges with beads 8 which are adapted to receive the upwardly extending flanges of preformed perforated metal panels 9 in the manner shown in Fig. 3. The flanges of the panels 9 are each provided with a bead 10 for co-operation with the beads 8 of the runners. By means of this construction a row of panels such as illustrated in Figs. 1 and 2 may removably be mounted between adjacent runners as in Fig. 3. A grid or the like 11 may be supported in each panel 9, and this grid may be made of wire or any suitable construction to support a sound absorbent pad 12 in spaced relation on the panel or tile.

In order to support the lamp control units, a channel iron 13 is secured to each row of hanger arms 3 by means of bolts 14, as in Figs. 3 and 4, or wire ties may be used, and at suitable intervals a resilient pad of shock absorbing material 15 such as felt is wrapped around the channel iron 13 in any suitable manner, for instance, as illustrated in Fig. 3. The lighting elements which are mounted in the elongated coffer spaces provided between the rows of panels comprise elongated wiring channel sections or so-called control units 16 which are of substantially the same length as the reflector sections. In ordinary practice, these units and sections may be substantially four feet long, although of course any suitable length may be used. The housings of the control units are preferably sheet metal substantially as shown in Fig. 3, and are provided at their lower edges with outturned flanges 17, which may or may not be attached to the reflector by self threading sheet metal screws. Cross bars 18 are provided with U-shaped hooked ends 19, and these bars are slightly longer than the space between the channel irons 13 whereby they may be placed over the channel irons and 75

then moved laterally so that they rest upon and engage the vibration material 15.

The control unit housings 16 are secured to and supported by the cross bars 18 by means of bolts or screws 19. This method of mounting prevents any appreciable transfer of the usual 60 cycle hum from the housing to the ceiling structure.

Trough-like reflector sections 20 are adapted to 10 be mounted in the coffer spaces and with their lower edges substantially flush with the face of the tile 9. These reflectors may be substantially bell shaped in cross section and flare outwardly adjacent their lower edges to form a comparatively large radius light diffusing arc at 21, which 15 arc forms substantially a continuation of the panel surface. That is, the panel surface is substantially tangent to the arcuate surface of the edge portion of the reflector. An important object of this arcuate formation of the reflector at 20 this point is to cause a considerable diffusion of light along the line of the edge of the reflector and prevent the sharp light cut-off line and consequent contrast adjacent the juncture of the 25 reflector and tile which is usual in this type of ceiling illumination. The outer edges of the reflector unit are provided with upturned flanges 22, which, when the ceiling is assembled, are closely adjacent the upturned flange of the tile 30 9 so that there is no appreciable space there-between.

Spaced holes are provided in the edges of the reflector sections whereby the reflectors may be secured to clamping brackets 23 by means of 35 screws 24, before or after the brackets are mounted on the runners 5, in the manner illustrated in Fig. 9. These brackets are adjustable longitudinally on the runners 5 to conform with the spacing of the holes in the reflector sections through 40 which the screws 24 extend. The brackets comprise a downwardly extending reflector supporting member 25 having a shoulder 26 thereon which engages the runner 5, as shown. The brackets are secured in spaced relation and clamped to the runner by means of the outwardly 45 extending clamp member 27, the outer end of which forms a hook portion 28 which engages around the outer edge of the runner. The two bracket members 25 and 27 are then secured together by means of a bolt 28.

As previously stated, the runners 5 are supported on the depending channel iron hangers 3 of the suspended framework and are secured thereto by one of the hanger brackets 23a by means of a bolt 29. The brackets 23a are slotted at 30 to enable alignment of the runners 5 all in the same plane irrespective of any inaccuracies in the framework. The reflectors are not secured to the hanger brackets 23a which support the runners, but only to the intermediate brackets 23 by means of screws 24. The reflector supporting brackets 23 are longitudinally adjustable on the runners to correspond with the holes in the reflectors. The reflectors are preferably always supported by the intermediate longitudinally adjustable bracket assemblies 23 (Fig. 9), and a number of these brackets, preferably three, may be mounted between the hanger arms 3.

The runners 5 are preferably made of comparatively light material and consequently are somewhat flexible, and it is desirable that the reflectors, which are comparatively rigid members, should assist in maintaining the alignment and rigidity of the ceiling. For this reason the hangers 3 are preferably spaced substantially the same

distance apart as the length of the reflectors and associated control units, which, in the present embodiment, are substantially four feet long. The hangers are therefore spaced so that one hanger may be positioned adjacent each end of a reflector. For instance, they may be approximately as shown in Fig. 4—that is, adjacent the overlapping joint of the reflector sections.

In order that the reflectors may be rigidly supported relative to the hangers, one of the adjustable runner brackets 23 is positioned closely adjacent each hanger for each reflector section. One or more of the brackets 23 are positioned intermediate the end brackets of each reflector section and, as these adjustable brackets are all secured to the edge of the reflector and the ends of the reflector are supported closely adjacent each hanger, the rigid reflector retains the flexible runner 5 and the panels supported thereon in horizontal alignment. The fact that the brackets 23 are adjustable on the runner 5 between the dependent hangers 3 is of great importance in maintaining all of the ceiling elements in alignment and at the same time enabling the use of few parts of comparatively light weight. Also, in case of misalignment at any time, it is only necessary to remove the reflectors and readjust the brackets on the hangers 3.

Fig. 10 is a side elevation, partially in section, of one of the brackets adapted solely for support of the runner 5. As previously stated, the reflector is not secured to the runner-supporting bracket. Therefore, in this embodiment the depending portion of the bracket member 25 is omitted and an L-shaped runner-clamping member 25a substituted therefor, and by which the runners may be clamped and secured as shown.

In assembling the ceiling, the runners 5 are first secured to the depending hangers 3 and the control units 16 are mounted on the sound-absorbent pads 15 on the cross bars 13. The reflector unit may then be pushed upwardly against the flanges of the control housing 16, as shown in Fig. 3, and the resilient insulating material 15 on which the reactance housing is supported enables sufficient self-adjusting movement of the housing to allow accurate locating and assembly of the reflector on the runner brackets 23. The preferred cross sectional shape of the reflector unit is illustrated in Fig. 7 and, as previously stated, these units are in sections preferably about 4 feet in length, and the ends of the sections are provided with overlapping portions as illustrated at 31 (Figs. 4, 5 and 6).

Fig. 5 is a fragmentary top view of the abutting and overlapping ends of the reflector sections shown in Fig. 4. One end of each reflector is provided with a sheet metal strip 31 welded thereto so that it overlaps the abutting end of the adjacent reflector as shown in Fig. 6. The central portions of these sections are merely brought together in abutting relation, as indicated at 32, and do not overlap. By this construction, the inner surfaces of the reflectors are retained in alignment. The overlapping strips may be secured by the usual thread-forming screws 33. The reflector ends are also notched as at 34 to provide space for the lamp sockets 35 to extend downwardly therethrough from the control unit housings 16 in which they are mounted. Fluorescent tubes 36 may be removably supported in the sockets 35. The ends of the control housings 16 are overlapped in the

same manner as the reflectors, as shown in Fig. 4, by means of a strip 16a.

The reflectors are provided with transverse baffle plates 37 which are shown in detail in Figs. 5 and 8. These baffle plates may be of sheet metal and are provided with reduced end portions 38 and 39, and the reflectors are provided with oppositely disposed slots 40 and 41 as shown. These slots are of just sufficient width to receive the reduced ends of the baffle plates, and the slot 40 is provided with a lateral extension slot 42 (Fig. 8) through which a laterally extending lug 43 on the baffle may be passed when the end of the baffle plate is inserted in the slot 40. The lateral extension slot 42 is spaced somewhat from the bottom of the vertical slot 40 and the slots 40 and 41 are somewhat longer than the width of the reduced ends 38 and 39 of the baffle plates. Therefore, the reduced end 38 may first be inserted through the slot 40 and extension slot 42 and then the opposite reduced end 39 of the baffle may be inserted in the oppositely disposed reflector slot 41 as shown. The ends of the baffle plates are notched at 44 and 45, respectively, so that the plate will be retained against longitudinal movement when in its operative latched position. The lug 43 provides a hinge for the baffle plate so that, when it is desired to service the lighting unit, it is only necessary to move the baffle plate 37 to the left (Fig. 7) and the plate will then pivot on the lug 43 and remain suspended in the position shown in dotted lines.

After the unit is serviced, it is only necessary to raise the baffle plates and insert the ends 37 in the slots in the manner previously described.

The invention herein disclosed provides a comparatively light illuminated acoustical ceiling which may be manufactured and assembled with a minimum of labor and expense. The elements 40 are so related that the ceiling surface may easily be aligned and the alignment will be retained through long service and may be realigned if required.

Also, the method of mounting the control units eliminates circuit noises and enables complete bench wiring of the control units, and permits erecting the housings in the ceiling independently of the reflectors or so-called coffers.

The lighting units may extend the entire length of a ceiling if desired or one or more sections may be used as desired. In Figs. 1 and 2 the end sections are each provided with an end wall 46 and small pans 47 and panels 48 are used together with full size panels to close the remainder of the coffer spaces.

It is intended, of course, that the invention should not be limited to the specific embodiment or embodiments disclosed herein, since many modifications may be made, and it is contemplated, therefore, by the appended claims to cover any such modifications as fall within the true spirit and scope of this invention.

Having thus described this invention, what is claimed and desired to be secured by Letters Patent is:

1. An illuminated ceiling comprising a framework having spaced runners forming alternate panel spaces and coffer spaces therebetween, panels supported by said runners in said panel spaces, and reflectors in said coffer spaces, said reflectors having spaced holes therethrough adjacent the edges thereof, brackets slidable on said runners to align with said reflector holes, and fasteners for securing said reflector to said slidable brackets through said holes.

2. A ceiling structure comprising a supporting frame constructed to provide panel spaces and intermediate coffer spaces, sound absorbent ceiling panels removably supported in said panel spaces, lighting fixtures supported in said coffer spaces, said lighting fixtures comprising elongated trough reflectors in end-to-end abutting relation and having their open edges substantially flush with said panels, said reflectors being coextensive with said panel spaces and forming an substantially arcuately curved continuation of the surface of said panels at each side of a coffer space and of a sufficiently large curvature to cause material light diffusion adjacent the edge of the reflector and prevent a sharp line light cutoff at said edge, and means to support elongated light sources in said reflector.

3. In an illuminated sound absorbent ceiling structure, cross beams suspended from a permanent support, spaced hangers suspended from said beams to provide alternate panel spaces and coffer spaces between rows of said hangers, runners secured adjacent the lower ends of said hangers, said runners having means associated therewith to removably support foraminated panels in said panel spaces, sound absorbent material supported on said panels, elongated coffer-like reflectors in said coffer spaces with their open edges flush with said panels, and clips on said runners and adapted to support said reflectors.

4. A ceiling structure comprising a supporting frame having spaced rows of vertical hangers providing alternate elongated panel spaces and coffer spaces, a panel-supporting runner horizontally supported on each row of hangers, sound absorbent panels in said panel spaces and supported by said runners, lighting fixtures in said coffer spaces and comprising elongated abutting reflector sections having their open sides substantially flush with said panels, brackets longitudinally adjustable on said runners between said hangers and independently of said hangers and panels, and means for securing said reflectors to said adjustable brackets whereby the open edges of said reflectors are substantially flush with the surface of said panels and closely adjacent thereto so that the reflector surface forms substantially an arcuate continuation of the panel surface.

5. A ceiling structure comprising a supporting frame having rows of spaced depending hangers, a panel-supporting runner secured to each row of dependent hangers to form alternate elongated panel spaces and coffer spaces, ceiling panels supported by said runners in said panel spaces, elongated lighting fixtures in said coffer spaces, said lighting fixtures comprising elongated control units supported by said dependent brackets and having resilient sound absorbent material therebetween, said control units being mounted to enable limited vertical movement, comparatively deep trough-like reflectors substantially bell-shaped in cross section in said coffer spaces below said control units and adapted to be pushed upwardly against said control units during ceiling assembly to enable relative self adjustment therebetween, and means to support said reflectors on said runners whereby the open edges of said reflectors are substantially flush with the panel surfaces and the reflector surface forms an arcuate continuation of said panel surface.

6. In an illuminated ceiling, spaced rows of vertical hangers for supporting said ceiling, ver-

70 tically adjustable brackets on said hangers, a horizontal runner secured to each row of brackets to provide alternate panel spaces and coffer spaces therebetween, panels supported by said 5 runners, a plurality of horizontally adjustable brackets on said runners, lighting fixtures in said coffer spaces and comprising elongated trough reflectors having their open sides flush with said panels and coextensive with said coffer 10 spaces, the edges of said reflectors being secured to said horizontally adjustable brackets.

7. In an illuminated ceiling the combination with a framework adapted to provide alternate panel spaces and coffer spaces and having ceiling panels in said panel spaces and elongated 15 flush type trough reflectors in said coffer spaces, of elongated control units supported on said framework by means of a cushion-like vibration absorbing support, said units having sockets extending into said reflectors to support light source elements, and means for mounting said units for self adjustment relative to said reflectors during assembly of said ceiling.

8. In an illuminated acoustical ceiling structure, rows of spaced hangers depending from a permanent support, runners secured adjacent the lower ends of said hangers to provide alternate panel spaces and coffer spaces therebetween, acoustical tile having upturned edges constructed for co-operative snap engagement with said runners to support said tile, elongated fluorescent control units in said coffer spaces and supported by said hangers for limited vertical and lateral self adjustment with trough-like reflectors inserted in said coffer spaces and supported by said runners.

9. In an illuminated acoustical ceiling structure, rows of spaced hangers depending from a support, runners secured adjacent the lower ends 40 of said hangers to provide alternate panel spaces and coffer spaces therebetween, acoustical tile having upturned edges constructed for co-operative snap engagement with said runners to support said tile, elongated fluorescent control units 45 in said coffer spaces and materially above said tile and supported for limited universal self adjustment with reflectors inserted thereunder and having dependent sockets to support fluorescent tubes, elongated trough-like coffer reflector sections 50 in said coffer spaces in self-adjusting contractual relation with said control units with said sockets extending within said reflectors to support fluorescent tubes therebetween, said reflectors being coextensive with said coffer spaces 55 and with their open sides substantially flush with the face of said panels, and means for supporting said reflectors by said runners.

10. In an illuminated ceiling, a row of hangers dependent from a support, a runner associated with said row of hangers, tile associated with said runner, said tile and said runner having complementary connecting portions interengaged to support said tile on said runner, a trough-like reflector snugly adjacent said tile 60 with its open side substantially flush therewith, and a plurality of longitudinally adjustable brackets on said runner whereby some of said brackets are positionable in accordance with said hangers for securing thereto and intermediate brackets are positionable in accordance with predetermined portions of said reflector for securing thereto.

11. In an illuminated ceiling, a row of hangers dependent from a support, a sheet metal flexible runner having a horizontal base and inturned,

downwardly extending, converging edges forming clamping flanges to receive the edge flanges of an acoustical tile in suspended supporting relation therebetween, means engaging the horizontal base of said runner for securing said runner to each of the hangers in a row, an elongated trough-like reflector section snugly adjacent said tile with its open side substantially flush therewith, and a plurality of brackets slideable on the base of said runner and having depending portions secured to the edge of said reflector in supporting relation at predetermined spaced points whereby said reflector section is supported adjacent each end by a bracket closely adjacent a hanger and whereby said flexible runner is secured to said more rigid reflector intermediate said end brackets.

12. In an illuminated acoustical ceiling having rows of hangers depending from a support and a sheet metal panel and reflector supporting runner secured to said hangers and having a horizontal base portion and a portion for supporting engagement with acoustical tile, a plurality of brackets longitudinally adjustable on said runners between said hangers, said brackets comprising a portion embracing said runner base portion and a depending portion secured to the flange of a coffer reflector for supporting said reflector with its open side substantially flush with said tile.

13. In an illuminated acoustical ceiling, the combination with a substantially T-shaped runner for supporting acoustical tile below said runner, of brackets longitudinally adjustable on said runner, said brackets comprising two strap-like portions adapted to embrace the head of said T-shaped runner, means to secure said portions together on said runner, one of said portions having an arm depending below said runner, and a coffer reflector secured to said arm with its open side substantially flush with an acoustical tile supported by said runner.

14. In an illuminated acoustical ceiling, a suspended runner, an acoustical tile, and an elongated comparatively deep trough-like reflector with their edges in flush juxtaposition below said runner and suspended therefrom, and an elongated fluorescent light source in said reflector, the inner reflecting surface of said reflector being arcuate with one or more centers of curvature remote from said light source and the reflecting surface adjacent said panel being substantially arcuate or rounded outwardly toward said panel sufficiently to form a convex continuation of the panel surface and prevent sharp light line cutoff.

15. In an illuminated a coustical ceiling, a suspended runner, an acoustical tile, and an elongated comparatively deep trough-like reflector with their edges in flush juxtaposition below said runner and suspended therefrom, an elongated fluorescent light source in said reflector, the inner reflecting surface of said reflector being arcuate with one or more centers of curvature remote from said light source and the reflecting surface adjacent said panel being substantially arcuate or rounded outwardly toward said panel sufficiently to form a convex continuation of the panel surface and prevent sharp light line cutoff, and freely removable baffle plates removably mounted in opposed slots in said reflector and loosely hinged thereto at one end so that they

may be laterally moved to release one end and suspended from said reflector by the hinged end to enable removal or insertion of said light source, the lower edges of said baffle plates being substantially flush with the lower edges of said reflector and the lower surface of said ceiling and substantially coextensive with the width of the open side of said reflector so that said ceiling has a substantially flat appearance when viewed angularly thereto.

16. In an illuminated acoustical tile ceiling, elongated sectional fluorescent lighting fixtures supported in said ceiling between rows of tile, said fixtures comprising a plurality of elongated fluorescent control units mounted end to end materially above the surface of said ceiling and having a depending socket at each end to receive a fluorescent tube therebetween, a plurality of deep trough sheet metal reflector sections, each of substantially the same length as its associated control unit and secured together in end-to-end partially abutting and partially overlapping relation to provide an aligned inner reflecting surface with openings therebetween for said sockets to extend therethrough into said reflectors when said reflectors are mounted in said ceiling and snugly against said housings, and means to support said reflectors independently of said housings and with their open sides substantially flush with said tile.

17. In an illuminated ceiling comprising spaced panels and an intermediate trough-like reflector with its lower edges substantially flush with the lower surface of said panels, said reflector having oppositely disposed vertical slots adjacent its edges and an opening forming a lateral extension of one of said slots, a baffle plate extending into said reflector and with its lower edge substantially flush with the lower surface of said panels and with the lower edges of said reflector, said baffle plate having its opposite ends resting on the bottoms of the respective slots, a lateral lug adjacent one end of said baffle plate and insertable through said lateral extension opening during the operation of inserting the baffle ends in said slots, said baffle being longitudinally movable in said slots whereby one end may be released from its slot and said baffle may be suspended from said reflector by said lug.

18. In an illuminated ceiling, a row of hangers dependent from a support, a runner associated with said row of hangers, tile associated with said runner, said tile and said runner having complementary connecting portions interengaged to support said tile on said runner, a trough-like reflector snugly adjacent said tile with its open side substantially flush therewith, a plurality of longitudinally adjustable brackets on said runner whereby some of said brackets are positionable in accordance with said hangers for securing thereto and intermediate brackets are positionable in accordance with predetermined portions of said reflector for securing thereto, means to enable vertical adjustment of the runner-supporting brackets on said hangers, and means accessible from the face of said ceiling to removably support said reflector so that said vertical adjusting means is accessible by removal of said reflector.
